DIE FOR MAKING A T-SHAPED PART

Harry Cadwallader, Jr., Philadelphia, Pa.

Application December 2, 1937, Serial No. 177,828

4 Claims. (Cl. 78—60)

The present invention relates to drop forging dies and more particularly to the drop forging of T-shaped parts, such as nuts, bolt heads, and the like.

5 In the manufacturing of T-shaped parts, it has heretofore been the practice to either machine a piece of oblong or square steel bar stock to shape, or to prepare a die having a parting line at right angles to the flanges and machined 10 to the required shape. Both of these prior methods require milling, planing, and cutting operations in the removal of excess metal, and to finish to shape, as well as centering for drilling, or hole sizing, and counter-sinking operations.

15 All of this work is not only costly in itself but requires jigs and special fixtures for each operation.

Some of the objects of the present invention are to provide a new and novel die for forging 20 T-shaped parts; to provide a forging operation wherein machining operations are reduced; to provide a die for forging T-shaped parts whereby special jigs and fixtures are not required after the forging operation; to provide a die for forging T-shaped parts whereby surfaces heretofore necessitating finishing operations are obtained 25 without such finishing operations; to provide a die for forging T-shaped parts wherein the parting line of the die is parallel to the top and bottom faces of the flanges; and to provide other 30 improvements as will hereinafter appear.

In the accompanying drawing, Fig. 1 represents a perspective of one part of a die embodying one form of the present invention; Fig. 2 represents a perspective of the other part of the die; Fig. 3 represents a section on line 3—3 of Fig. 1; Fig. 4 represents a section on line 4—4 of Fig. 2; Fig. 5 represents a perspective of the T-shaped part as formed by the coaction of the die parts of Figs. 1 and 2; Fig. 6 represents a section on line 6—6 of Fig. 5; and Fig. 7 represents a sectional elevation of a modified form of die.

Referring to the drawing, one form of the present invention consists of a die formed by parts 45 10 and 11, which are arranged to abut on faces 12 and 13 as the parting line of the die. The die part 10 is formed with the cavity 14, which is complementary in configuration to the shape of 50 one portion of the article to be forged, and, in this instance, is formed by two substantially rectangular walls 15 and 16 of different width but of the same length. The wall 15 joins the wall 16 along two opposite sides by two surfaces 17, 55 lying in the same horizontal plane, and having

the function of forming the two upper finished faces 18 on the flanges 20 of the forged part 21. That portion of the cavity 14 bounded by the walls 16 is shaped to form the substantially rectangular base block 22 of the finished part. 5

In order that the shank receiving hole 23 of the article can be partially formed during the forging operation, the bottom of the cavity 14 is provided, in the proper location, with a forming projection 24 of substantially conical shape, 10 and of a length just sufficient to displace the amount of metal necessary to create a depression without causing an excess of metal being forced into an adjoining area, where its presence is detrimental to the proper shaping and finishing of the flat surfaces. 15

The die part 11, which coacts with the part 10 to form a complete forging, is provided with a cavity 25 complementary in configuration to the shape of that portion of the article which is not 20 shaped by the die 10. This cavity 25, in the present instance, is formed by a substantially rectangular wall 26, and a bottom 27, the dimensions being such that when the two die parts 10 and 11 are in face to face operative position, the 25 two cavities 14 and 25 register one with the other to form a complete metal shaping chamber.

In order that the shank receiving hole 23 may be partially formed in the bottom of the head portion of the forged part, a centrally disposed 30 projection 28 is located in the cavity 27 in such a position that it takes a coaxial relation with the projection 24 when the two die parts are superposed. Thus the two projections 24 and 28 function to center and form two holes respectively at 35 the top and bottom of the forged part, whereby a minimum of drilling is required, and the usual centering operation eliminated.

Attention is directed to the fact that since the parting plane 30 is in the head and lies parallel to the bottom of the head, as well as the surfaces 18, the bounding walls 15, 16 and 26 can be shaped with a minimum of angularity, thereby permitting the die to be drawn easily without roughened edges or irregular corners. In other 45 words the base block 22 as forged by the present invention is accurately dimensioned for correct coaction, with a machine slot of the T-type.

In Fig. 7 a modified form of the invention is shown wherein provision is made to form a 50 counter-sink about the two holes formed by projections 14 and 28. Thus the projection 14 in die part 10 is encircled at its base by a bevelled surface 31, and the projection 28 in die part 11 is encircled at its base by a bevelled surface 32. 55

These surfaces 31 and 32 are properly dimensioned in order to respectively form similar depressions about the ends of the shank hole 23.

It will now be apparent that a complete unitary die has been devised for making drop forgings of T-shape, and wherein the plane of parting is in the head and is parallel to the main flat surfaces of the article instead of at right angles thereto as has heretofore been the general practice. This shifting of the plane of parting results in new and unexpected results in that surfaces which had to be heretofore milled, planed and finished, are now finished in the forging operation. Also the centering operation for the shank hole is dispensed with, as also the major part of the drilling.

While one form of the invention and a modification thereof are shown, it is to be understood that the invention is not limited to the exact construction as shown but may be varied according to requirements without departing from the spirit of the invention. For example the projections 24 and 28 are preferably formed as integral with the die parts, but it is to be understood that these might be removable inserts and still be within the scope of the invention.

Having thus described my invention, I claim:

1. As a new article of manufacture, a two part die for forging a T-shaped nut blank, having its parting plane in the head of the T and parallel to the top and bottom faces of the flanges forming the head.

2. As a new article of manufacture, a two part die for forging a T-shaped nut blank, having its parting plane in the head of the T and parallel to the top and bottom faces of the flanges forming the head and having a punching projection on one of its parts.

3. As a new article of manufacture, a two part die for forging a T-shaped nut blank, having its parting plane in the head of the T and parallel to the top and bottom faces of the flanges forming the head and having a punching projection on each of its parts.

4. As a new article of manufacture, a two part die for forging a T-shaped nut blank, having its parting plane in the head of the T and parallel to the top and bottom faces of the flanges forming the head and having a punching projection on each of its parts, said projections being coaxially aligned.

HARRY CADWALLADER, JR. 25
